(57) **CLAIM**

The ornamental design for a storage tank for dump body, as
shown and described.

DESCRIPTION

FIG. 1 is a top front perspective view of a storage tank for
dump body showing our new design;

FIG. 2 is a bottom front perspective view of the storage tank
for dump body illustrated in FIG. 1;

FIG. 3 is front view of the storage tank for dump body
illustrated in FIG. 1;

FIG. 4 is a rear view of the storage tank for dump body
illustrated in FIG. 1;

FIG. 5 is a left side view of the storage tank for dump body
illustrated in FIG. 1;

FIG. 6 is a right side view of the storage tank for dump body
illustrated in FIG. 1;

FIG. 7 is a top view of the storage tank for dump body
illustrated in FIG. 1;

FIG. 8 is a bottom view of the storage tank for dump body
illustrated in FIGS. 1; and

FIG. 9 is an in use view of the storage tank for dump body
illustrated in FIG. 1;

FIG. 10 is a top front perspective view of a storage tank for
dump body showing our new design;

FIG. 11 is a bottom front perspective view of the storage
tank for dump body illustrated in FIG. 10;

FIG. 12 is front view of the storage tank for dump body
illustrated in FIG. 10;

FIG. 13 is a rear view of the storage tank for dump body
illustrated in FIG. 10;

FIG. 14 is a left side view of the storage tank for dump body
illustrated in FIG. 10;

FIG. 15 is a right side view of the storage tank for dump
body illustrated in FIG. 10;

FIG. 16 is a top view of the storage tank for dump body
illustrated in FIG. 10;

FIG. 17 is a bottom view of the storage tank for dump body
illustrated in FIG. 10; and,

FIG. 18 is an in use view of the storage tank for dump body
illustrated in FIG. 10.

In the drawings, the broken lines depict portions of the
article that form no part of the claimed design.
